UNITED STATES PATENT OFFICE.

FREDERICK C. FARNSWORTH, OF BROOKLYN, NEW YORK.

APPARATUS FOR HANDLING AND DELIVERING WATER.

1,118,644.

Specification of Letters Patent.

Patented Nov. 24, 1914.

Application filed March 31, 1914. Serial No. 828,461.

To all whom it may concern:

Be it known that I, FREDERICK C. FARN-
SWORTH, a citizen of the United States, and
resident of Thirty-sixth street and Second
5 avenue, Brooklyn, county of Kings, and
State of New York, have invented an Im-
provement in Apparatus for Handling and
Delivering Water, of which the following is
a specification.

10 My invention relates to an effective appa-
ratus for handling and delivering water and
consists of certain improvements which are
fully set forth in the following specification
and shown in the accompanying drawings
15 which form a part thereof.

The object of my invention is to provide
an effective mechanism for collecting, han-
dling and delivering water, such as water of
condensation, and which is adapted to auto-
20 matically discharge or deliver, in an inter-
mittent manner, volumes of the collected
water to a suitable point of use either against
atmospheric pressure or pressure above, as
the case may be.

25 My object is further to provide a construc-
tion which is quick and positive in action,
rapid in operation, and which does not re-
quire the use of packing or complicated
valve mechanism, thereby eliminating the
30 liability of the parts clogging or otherwise
becoming inoperative through defects in
such delicate mechanism.

35 My object is further to provide an im-
proved normally balanced receptacle for
water, which is controlled by gravity and
has its associated fixed parts connected to
the movable adjuncts through the medium of
40 flexible connections, thereby permitting free
unobstructed movement of one part with re-
spect to another.

45 My invention comprehends features of
construction in a machine of this form,
which are fully described hereinafter and
more particularly defined in the claims.

50 These improvements will be better under-
stood by reference to the drawings, in
which:

55 Figure 1 represents a side elevation of an
apparatus, for handling and delivering
water, which embodies my invention; Fig. 2
represents a plan of the apparatus with the
tank shown in dotted lines; Fig. 3 represents
a longitudinal section of a portion of the
flexible connections used in connection with
55 the apparatus; Fig. 4 represents a section on
line $\alpha-\alpha$ of Fig. 1; Fig. 5 represents a sec-

tion on line $y-y$ of Fig. 1; Fig. 6 represents
a longitudinal section of the apparatus.

Similar numerals of reference indicate
corresponding parts.

1 designates a suitable bed for the appa-
ratus, provided with a number of suitable
pedestals or supports 2 for respectively sup-
porting different fittings of the steam and
water pipes forming adjuncts of the appa-
ratus. Certain of these supported fittings
60 are utilized as bearing members for a sub-
stantially cylindrical casting 3 which is here
shown as carried by trunnions 4 and pro-
vided also with channels 5 and 6.

7 designates a tank or receptacle which
may be made of sheet metal or otherwise,
and is divided by a partition 8 into two com-
partments 9 and 10, the former having com-
munication with the channel 5 by way of the
75 coil of pipe 11 and nipple connection 12
while the latter communicates directly with
the channel 6 by way of the nipple 13. The
chamber 9 is preferably somewhat longer
than the chamber 10 for a purpose which
80 will later appear. It will be understood that
the casting 3 is preferably provided with
suitable heads 14 adapted for connection
directly to the bottom of the tank and also
that the tank is suitably apertured to receive
85 the aforesaid nipple connecting members.

15 designates a second coil of pipe suit-
ably supported within the chamber 10 and
having one end thereof passing through the
partition 8 and connected for communica-
90 tion with a suitable T-fitting 16 with which
the nipple 12 and end of the coil 11 are also
connected. The opposite end of the coil 15
projects through the partition 8 as shown at
17 adjacent the top of the chamber 9 and in
95 close proximity to the upper outlet 18 of the
coil 11.

19 designates a pipe vertically disposed
within the chamber 10 and having connec-
tion with a horizontally arranged pipe 20
which passes through the partition 8 so that
its open end 21 is within the compartment 9.
The pipe 19 further is provided with a re-
turn bend 22 supporting the open ended pipe
23, the lower end of which is positioned at
105 the normal water level within the compart-
ment 10 necessary to maintain the tank 7 in
horizontal position and resting upon the
buffer 24 fixed to the bed 1. At the opposite
side of the pivotal point of the tank 7, with
110 respect to the buffer 24, there is a second
buffer 25 also secured to the bed 1 and sub-

stantially shorter than the buffer 24 so that the tank may have free swinging movement within the determined limits.

In the present instance I have shown the apparatus connected for handling water of condensation and exhaust steam and delivering the same as preheated feed water to a boiler, but I do not desire to be restricted to this particular application or use.

26 designates the return pipe from whatever systems are connected thereto for conveying the water through the check valve 27, T-fitting 28 to the flexible tube or conduit 29 which is connected to the casting 3 and 15 has communication with the conduit 6. In addition to the return of condensed water, the pipe 26 also receives by way of pipe 30 exhaust steam from the exhaust line 31 which is connected to a four-way fitting 32 and 20 and communicates with the pipe 30 by way of the pipe 33 and check valve 34. The pipe 33 also carries a valve 35, of the ordinary balanced type, between the fitting 32 and check valve 34 for a purpose which will 25 be presently described. 36 designates a flexible tube or conduit connected at one end to one of the openings in the fitting 32 and at the opposite end has communication with the channel 5 where it is connected to the casting 3. The remaining opening in the fitting 32 has communication with a valve member 37, also of the ordinary balanced type and connected to the live steam pipe 38. The valve members 35 and 37 are so arranged 30 as to alternately open and close, that is to say, when one is open the other is closed, and vice versa. These valves are operated, in the present instance, by a lever 39 fulcrumed upon the standard 40 and connected 35 respectively on opposite sides of the fulcrum with the valve stems 41 and 42 for the respective valve members 35 and 37. It will be noted that the free end of the lever 39 is 40 preferably provided with an opening 43 for the reception of a lug or pin 44 carried by 45 the tank 7, the said opening having a clearance about the pin 44 so that the latter has a slight movement before it engages the lever 39. The function of this construction 50 is to cause the impact of the moving pin 44 to insure a prompt opening of the steam valve 37 and a simultaneously quick closing of the valve 35.

45 designates the delivery pipe from the apparatus the same having connection with the T-pipe fitting 28 and having a check valve 46 therein to prevent return of the water under greater pressure than existing in the apparatus. A check valve 46 is also 55 provided in the exhaust line 31 to prevent back flow to the pipe, as will be readily seen.

In the operation of the apparatus the compartment 10 of the tank 7 normally contains sufficient water to maintain the tank in horizontal position as shown in Fig. 1, in which

position the live steam valve 37 is held closed while the valve 35 is open since the lever 39 is in its uppermost position. The water enters the apparatus by way of the pipe 26 and may flow freely by gravity through the flexible conduits 29 and channel 6 into the chamber 10. This flow of water may be augmented by the exhaust steam discharging through the pipes 31, 33 and 30 into the return 26 as will be understood, though a portion of this exhaust steam may also traverse the conduit 36, channel 5 and enter the coils 11 and 15 in the respective chambers 9 and 10 where it serves to heat the water collecting within the tank. As the water level 75 moves upward within the chamber 10 it enters the depending pipe 23 rising therein until the level reaches the return bend 22 when a siphoning action takes place, starting a flow of the water within the compartment 80 10 by way of the pipes 19 and 20 into the compartment 9, which flow continues until the level of the water within the compartment 10 falls below the inlet of pipe 23. The transfer of the water from one compartment 85 to the other shifts the center of gravity of the tank 7 from one side of the pivotal support of the tank to the other, and consequently the tank tilts to a new position, resting at an incline upon the buffer 25. This 90 tilting action operates the lever 39 to close the balanced valve 35 and open the balanced valve 37 so that live steam from the pipe 38 is admitted to the conduit 5 from which it 95 is distributed through the two sets of coils 100 11 and 15 and discharges into the compartment 9. The admission of this pressure into the compartment 9 forces the water contained therein back through the pipe 20 into the chamber 10 from which it is forced under the same pressure through the channel 6 and conduit 29 to the delivery pipe 45. The check 46 in this latter pipe is arranged for free flow in the direction of the arrow shown. The delivery continues until the 105 quantity of water in the compartment 10 overbalances the opposite side of the tank 7, thus causing it to return to normal horizontal position, during which movement of the lever 39 closes the live steam valve 37 and 110 again opens the valve 35.

Attention is directed particularly to the manner in which the tank is journaled and also to the flexible conduits which permit free movement between the fixed and movable parts, this obviating the use of packing to prevent leakage between moving parts, and the objectionable friction produced thereby. Furthermore, the valves which are controlled and operated by the movement of the tank are quick acting, positive, and the operating parts are so constructed and arranged as to insure the prompt movement of the valves. The invention is also important 125 in that a system of heating the circulated 130

water by the steam employed to move it (with or without auxiliary exhaust steam) may be employed. It will further be seen that all of the parts are so proportioned as 5 to operate positively in a definite manner and all ports and passages are of large size, whereby it is evident that there is no possibility of the same clogging or becoming defective in their operation. It will also be 10 noted that by my present construction I have dispensed with all float mechanisms and all means which require delicate adjustment or manipulation, and consequently my improved apparatus is easily installed, easily 15 kept in order and very positive in its operation.

While I have shown my present apparatus as more particularly arranged for handling and delivering feed water to a boiler, I do 20 not wish to be restricted to this particular use, as obviously the delivery pipe may be connected to any type of mechanism in which water, or preheated water, is to be used, and furthermore the delivery pipe may 25 be of any desired length and have its outlet remote or at a distance from the tank structure.

It will now be apparent that I have devised a novel and useful construction which 30 embodies the features of advantage enumerated as desirable, and while I have in the present instance shown and described the preferred embodiment thereof which has been found in practice to give satisfactory 35 and reliable results, it is to be understood that I do not restrict myself to the details, as the same are susceptible of modification in various particulars without departing from the spirit or scope of the invention.

40 In this application, no claim is made to the special arrangements of the flexible conduits or pipes 29 and 36, in so far as they are arranged parallel to the axis of oscillation of the tank and are in communication 45 with the chambers of the tank and respectively with the water and steam pipes, as this specific arrangement forms subject matter of my application Ser. No. 847,887, filed June 29, 1914.

50 Having thus described my invention, what I claim as new and desire to protect by Letters Patent is:—

1. In a device of the character stated, the combination of a tank divided into two compartments and suitably mounted to tilt from one position to another, a water supply and delivery pipe, a flexible conduit forming a communication between one of said tank compartments and said water pipe, a steam supply pipe, a flexible conduit forming a communication between the remaining tank 55

compartment and said steam pipe, means operable by the movement of said tank for controlling the admission of steam to said latter compartment, and means having communication with said flexible steam conduit for conveying the steam through both of said compartments and discharging it adjacent the top of the same compartment. 65

2. In a device of the character stated, the combination of a tank divided into two compartments and suitably mounted to tilt from one position to another, a coil located in one of said chambers and provided with an open end adjacent the top of said chamber, a coil 75 located in the other chamber and having its ends terminating in the first chamber, one of said ends being connected to the first mentioned coil and the other end in free communication with the chamber, a steam 80 conduit passing through the walls of said tank and connecting with both of said coils, said conduit having a flexible portion connecting the fixed and movable part thereof, a conduit for water having communication 85 with the first chamber and provided with a flexible portion connecting the fixed and movable parts of said conduit, a valve controlling said steam conduit and means operated by the movement of said tank for opening said valve to admit steam to said coils, and means for siphoning the contents of one 90 chamber into the other chamber.

3. In a device of the character stated, the combination of a tank divided into two compartments, a trunnion member supporting said tank for tilting movement and having a plurality of channels therethrough, a water supply and delivery pipe, a flexible conduit forming a communication between one of 100 said trunnion channels and said water pipe, a steam supply pipe, a flexible conduit forming a communication between the other trunnion channel and said steam pipe, said trunnion channels communicating respectively 105 with said tank compartments, an exhaust steam pipe having communication with said steam channel, a by-pass leading from said exhaust steam pipe to said water supply pipe, a valve in said by-pass pipe, a second 110 valve in said steam supply pipe, means for causing the water to pass from one compartment into the other compartment, and means operable by the movement of said tank for alternately opening and closing said valves. 115

In testimony of which invention, I hereunto set my hand.

FREDERICK C. FARNSWORTH.
